(57) CLAIM

An ornamental design for a combined lip balm holder and bottle opener, as shown and described.

DESCRIPTION

FIG. 1 is a PERSPECTIVE view of an embodiment of the present invention;

FIG. 2 is a FRONT view of an embodiment of the present invention;

FIG. 3 is a BACK view of an embodiment of the present invention;

FIG. 4 is a SIDE view of an embodiment of the present invention;

FIG. 5 is a SIDE view of an embodiment of the present invention;

FIG. 6 is a TOP view of an embodiment of the present invention;

FIG. 7 is a BOTTOM view of an embodiment of the present invention; and,

FIG. 8 is a PERSPECTIVE view of an embodiment of the present invention.

The broken lines shown in the drawings illustrate the environment of the article and form no part of the claimed design.
